BOX

Jerome Shiffman, 128 Cartage Road, Scarsdale, N.Y.

Filed Mar. 31, 1964, Ser. No. 79,262

Term of patent 7 years

(Cl. D58—12.7)

FIG.1

I claim:

The ornamental design for a box, as shown and described.
